UNITED STATES PATENT OFFICE.

JOHN SPRINGER, OF CLINTON, ASSIGNOR OF ONE-HALF TO MARTIN C.
MOORE, OF PRAIRIE DU SAC, WISCONSIN.

HOT-AIR REGISTER.

SPECIFICATION forming part of Letters Patent No. 380,145, dated March 27, 1888.

Application filed June 3, 1887. Serial No. 240,183. (No model.)

To all whom it may concern:

Be it known that I, JOHN SPRINGER, of Clinton, in the county of Rock and State of Wisconsin, have invented new and useful Improvements in Hot-Air Registers; and I do hereby declare that the following is a full, clear, and exact description thereof, reference being had to the accompanying drawings, which form a part of this specification.

10 This invention relates to certain new and useful improvements in hot-air registers; and the invention consists in the peculiar construction and arrangement of the parts, whereby means are provided for protecting the floor or 15 wood-work in which the register may be placed, and for producing a more thorough circulation of air within the apartment, all as more fully hereinafter set forth.

Figure 1 is a perspective view showing the 20 top perforated plate detached from the main pan or box. Fig. 2 is a vertical cross-section with the two parts put together.

In the accompanying drawings, which form a part of this specification, A represents a register box or case provided with the laterally-projecting flange B, and preferably I cast the 25 two integrally with each other. The bottom of the box A is provided with a collar, C, by means of which said box may be connected 30 with a hot-air pipe, as in the ordinary manner, and in this collar is properly journaled a damper, D.

E is an upwardly-projecting flange or partition rising from the bottom of the box A, thus 35 forming an inner chamber, M, and an outer chamber, N, between such partition and the outer vertical walls of the box. Properly journaled to one of the side walls of this partition E is a disk or wheel, F, the periphery of 40 which projects above the top of the box A. This disk or wheel is provided with a crank-lever, G, the free end of which latter is connected, by means of a rod, H, to the damper D in such a manner that by a partial rotation 45 of the disk the damper can readily be turned to close or unclose the opening through the collar.

I is the top perforated plate provided with the two sets of perforations a b, respectively,

near the outer edges of the sides and ends and 50 above the chamber N, and with the larger perforations, c, the latter being directly over the chamber N. To the under side of the top plate, I, is secured the pendent flange J, its upper edge being secured to the top plate between the sets of perforations a b, as shown.

In practice, when the top plate is in position, it rests upon the top of the partition E and lies flush with the top of the flange B. The pendent flange J of the top plate enters 60 the space N between the partition E and the outer walls of the box and extends nearly to the bottom thereof. The hot air enters the box through the collar, and is distributed to the apartment through the perforations c of 65 the top plate, while the air-space surrounding the inner chamber keeps the adjacent wood-work cool and avoids all danger from fire. It will also be found that the air at the floor of the room will be drawn down through the 70 outer row of holes, a, under the flange J, and be again discharged into the apartment through the holes b, and that such air will have been warmed by coming in contact with the partition or flange E.

If it is desired, water may be put into the air-space N surrounding the inner chamber, which will by evaporation impart a suitable moisture to the air within the apartment.

The damper can readily be opened or closed 80 by operating the disk or wheel, which projects slightly above the top plate.

What I claim as my invention is—

The case A, formed with laterally-projecting flange B, collar C, and partition E, forming an 85 inner chamber, N, and an outer chamber, M, combined with the perforated top provided with large perforations over the inner chamber and smaller perforations over the outer chamber, and with a pendent flange, J, extended vertically between the partition E and the outer wall of the case A, substantially as 90 and for the purpose specified.

JOHN SPRINGER.
